UNITED STATES PATENT OFFICE.

CHARLES C. BACON, OF PHILADELPHIA, PENNSYLVANIA, ASSIGNOR TO ROSS-TACONY CRUCIBLE COMPANY, OF PHILADELPHIA, PENNSYLVANIA, A CORPORATION OF PENNSYLVANIA.

BAYONET-JOINT LADLE STOPPER.

Application filed November 20, 1928. Serial No. 320,569.

The present invention is supplemental to that of my Patent No. 1,698,876 and, application #279,879 filed May 23, 1928, and covers another type of stopper head than either 5 of them.

The invention relates to improvements in stoppers for bottom pour ladles used to contain molten metal.

The principal object of the present invention 10 is to provide a stopper for use in controlling the flow of molten metal from a ladle which will not be damaged in fitting to the stopper rod or when unusual strain is put upon it.

15 Usually the closed end, bayonet joint ladle stopper is attached to the rod by turning it so that the transverse metal pin engages the horizontal slot in the stopper. The sleeves are adjusted on the rod with sufficient slurry 20 between and held down firmly by fastening means at the upper end of the rod. The force exerted for adjusting the sleeves may draw the pin into the softer clay, or clay and graphite, of the stopper to the great danger 25 of seriously damaging it with resultant failure during the pouring operation.

If a skull of chilled metal has formed in the metal in the ladle, the extra force required to release and lift the stopper may cause the 30 metal pin to be drawn through the clay or clay and graphite above the slot, resulting in the loss of the stopper and thereby all control of the metal in the ladle.

When, as is sometimes necessary, (and frequently when not) the stopper is pounded 35 down against the nozzle a similar shearing may result and the stopper head be lost.

My invention comprises the improvements to be presently described and finally claimed.

40 Figure 1 is a side elevation of the ladle stopper rod assembly.

Fig. 2 is a top elevation of the stopper head.

Fig. 3 is a vertical cross section through the stopper head, and

45 Fig. 4 is a detail of an insert channel.

Referring to Fig. 1 the ladle stopper rod assembly consists of a rod 1 having a pin 2 passing through the lower end thereof. At the upper end of rod 1 are mounted nut 10 and washer 3 which form a fastening means for a plurality of sleeves 4 which are mounted 50 on and which surround rod 1. On the

lower end of rod 1 is mounted stopper head 5 which has hole 6 through the upper end thereof to admit rod 1. Partway of the axial 55 length of hole 6 are horizontal grooves 7 into which are fitted channel inserts 9. The grooves 7 are shaped like segments of circles. On opposite sides of hole 6 are formed vertical slots 8 which give access each to one end of one of the grooves 7. Mounted in the opposite ends of grooves 7 from the slots 8 are channeled inserts 9 made of metallic or suitable material having a high melting point. The opening 6 is flared at its upper end to 65 provide ready entrance to rod 1. Pin 2 descends through slots 8 and rod 1 is then rotated to cause pin 2 to rest against the ends of slots 7 in contact with channels 9. Thus it will be seen that channels 9, take the strain 70 when rod 1 is moved in a vertical direction. This results in a much stronger stopper head.

It will be obvious to those skilled in the art to which the invention relates that modifications may be made in details of construction 75 and arrangement, and in matters of mere form without departing from the spirit of the invention which is not limited as to such matters or otherwise than the prior art and the appended claims may require.

I claim:

1. A ladle stopper head of refractory material provided with a closed end and having a recess and two channel members anchored in the recess substantially as and for the purposes described.

2. A ladle stopper rod assembly comprising in combination, a metallic rod, a pin through one end thereof, a stopper head of refractory material having bayonet slots 90 therein adapted to receive the pin on said rod and channel members mounted at the inner ends of said bayonet slots.

3. A ladle stopper head of refractory material having an axially arranged concavity 95 provided with straight, confronting, axially disposed open slots and with opposed grooves circumferentially arranged, each of the form of a segment of a circle, and each connected at one end with one of said slots and each provided near its other end and as a continuation thereof with a ground insert of the form of a segment of a circle.

CHARLES C. BACON.
